(57) **CLAIM**

The ornamental design for a display system with a virtual three-dimensional graphical user interface, as shown and described.

DESCRIPTION

FIG. 1 is a front view of a display system in which the virtual three-dimensional graphical user interface of my new design, depicting the top, front, left perspective view orientation;

FIG. 2 is a second orientation thereof, in which the virtual three-dimensional graphical user interface is shown in the bottom, front, right perspective view;

FIG. 3 is a third orientation thereof, in which the virtual three-dimensional graphical user interface is shown in the front elevation view;

FIG. 4 is a fourth orientation thereof, in which the virtual three-dimensional graphical user interface is shown in the left side view;

FIG. 5 is a fifth orientation thereof, in which the virtual three-dimensional graphical user interface is shown in the right side view;

FIG. 6 is a sixth orientation thereof, in which the virtual three-dimensional graphical user interface is shown in the top plan view; and,

FIG. 7 is a seventh orientation thereof, in which the virtual three-dimensional graphical user interface is shown in the bottom plan view.

The virtual multi-dimensional graphical user interface in FIGS. 1-7 is shown in various orientations to provide an understanding of the three-dimensional appearance of the design.

The rear elevation view of the virtual three-dimensional graphical user interface is not visible during ordinary use and forms no part of the claimed design.

The broken lines of uneven length represent the field of view for the visual display and form no part of the claimed design.
